UNITED STATES PATENT OFFICE

GEORGE R. KRESS, OF LOS ANGELES, CALIFORNIA

BUILDING-WALL-MOVING DEVICE

Application filed February 11, 1929. Serial No. 339,025.

My invention relates to the art of moving parts of buildings and relates more specifically to a device whereby the front or rear wall of a building may be moved bodily to a desired location.

It has frequently happened that a necessity arises to move buildings back from the street or move the front of the building to a new line consequent to the widening of a street. Ordinarily in such cases the front wall of a building is torn down and rebuilt which operation entails considerable expense.

It is the principal object of my invention to provide a device whereby a wall of a building may be moved intact to the desired location.

Other objects and advantages of my invention will appear from the following description. Referring to the drawings which are for illustration purposes only

Fig. 1 is a vertical sectional view through the front wall of a house showing a device embodying a form of my invention erected in connection therewith.

Fig. 2 is an enlarged sectional view on line 2—2 Fig. 1.

Fig. 3 is an enlarged sectional view on line 3—3 Fig. 1.

Fig. 4 is a diagrammatic inside face view of a front wall of a house showing the moving device shown in Fig. 1.

More particularly describing the form of my invention shown in the drawings, 11 designates timbers which are placed against both the inside and outside of the wall 12 to be moved. These timbers are arranged in pairs, that is one timber on the rear of the wall being associated with a similarly disposed timber on the front of the wall, the disposition of the pairs of timbers and the number used on the wall depending on the size and character of the wall to be moved. In the present instance I have shown two pairs or sets of timbers diagonally disposed as shown in Fig. 4.

The related timbers of each pair are clamped to the wall at each floor in the following manner—15 designates channel bars fitted over the timbers, each having an opening therein to receive a threaded bolt 16, an

opening 17 having been made through the wall to receive the bolt. Nuts 18 and 19 are tightened against the respective channel bars 15 so as to clamp the timbers firmly against the wall. The inner end of the bolt 55 16 extends through one plate 20 of a connector or coupling member 21 being provided with a head 22 engaging against the inner face of the plate 20. The connector consists of the plate 20 and a similar plate 24 held in spaced relation to each other by means of bolts 25.

The plate 24 receives a shaft 27 rotatable therein and provided with a head 28 bearing against the inner face of the plate 24. The 65 shaft 27 is threaded as indicated at 29 and such threaded portion extends through nuts 30 which are prevented from turning by being welded to plates 31 which in turn are welded to angle-irons 32 riveted to a base 70 plate 33 which is secured to a floor 35 of the building by means of screws 36 as clearly shown in Fig. 2. The inner end of each shaft 27 is provided with a head 37 having openings 38 to receive a crow bar or lever 39.

In the form shown I have indicated two sets of timbers 11 and two jack or drawing devices, one on each of the upper floors of the buildings, it being understood that each set of timbers used is arranged with cooperating jacks or drawing devices as above described.

The wall supporting portion of the device consists of the following structure which can best be understood if the same is described 85 as actually used for instance as follows: Openings are made through the front wall 12 as indicated at 40 and a track consisting of rails 41 and ties 42 laid through the opening.

Upon the track 41 are placed a number of rollers 43 which support a steel shoe 44 secured to the underside of a platform of timbers 45. Mounted on the platform 45 are vertically extending braces 46 converging at 95 their upper ends under a beam or joist 47 usually formed in a wall at the level of the second floor. In the form shown two of the wall supporting devices are used, it being understood that when placed in position as 100

above described, such devices entirely support the front wall 12.

After the supports are in place, the front wall is severed from the foundation 49 as generally indicated at 50 in Fig. 4 after which the floor timbers or joists 52 are cut off as indicated at 51. The wall 12 now being free of the house and supported on the rollers 43, the shafts 27 are rotated simultaneously and the wall moved back to the desired position as indicated in dotted lines in Fig. 1, after which connection is made between the wall 12, the floor joists 52 and the new foundation indicated in dotted lines at 54 in Fig. 1.

It will be apparent from the foregoing description, that applicant's invention comprises an organization which is especially adapted for use in moving a movable section 20 of a building, such as a wall, away from or toward and into engagement with a stationary building section.

The term "jack means" used in the appended claims is meant to include a stationary or fixed support such as the floor member 51, the screw 27, and the cooperating block 32, or its equivalent part.

It is to be understood, that while I have herein described and illustrated one preferred 30 form of my invention that the invention is not limited to the precise construction set forth above, but includes within its scope whatever changes fairly come within the spirit of the appended claims.

35 I claim as my invention:

1. A wall moving device comprising a movable wall supporting means and a plurality of horizontally disposed and vertically spaced jack means engaging said wall.

40 2. A wall moving device comprising a movable wall supporting means; a plurality of sets of wall engaging means and horizontally disposed jack means cooperating with each set of wall engaging means.

45 3. A wall moving device comprising a wall supporting means, rollers supporting said wall supporting means, a timber on each side of the wall, means for clamping the timbers to the wall, and horizontally disposed jack means connected to said clamping means.

50 4. A house wall moving device comprising, a wall supporting means, rollers under the wall supporting means, a plurality of sets of timbers engaging said wall, each set consisting of a timber on each side of the wall, bolts extending through the wall and each set of timbers, nuts on said bolt clamping the timbers to the wall, a jack screw for each bolt, a coupling connecting each jack screw with its associated bolt, and means for supporting said jack screws.

55 5. A house wall moving device comprising, a wall supporting means, rollers supporting said supporting means, sets of timbers on each side of said wall, each set consisting of a

timber on each side of the wall, clamping means for securing the wall between the timbers, horizontally disposed jack means cooperating with the clamping means, and means for securing said jack means to a stationary part of the house. 70

6. A device for moving a wall into engaging relation with a stationary section of a building, embodying movable wall supporting means; and means attached to said stationary section for pulling said wall toward said building. 75

7. A device for moving a wall into engaging relation with a stationary section of a building, embodying movable wall supporting means; and means attached to said stationary section at different levels therein for pulling said wall toward said building. 80

8. A device for moving a wall into engaging relation with a stationary section of a building, embodying: movable supporting means beneath said wall; and wall moving means comprising screws, each having one end attached to said wall and the opposite end attached to said stationary section. 85

9. A device for moving a wall into engaging relation with a stationary section of a building, embodying: movable supporting means beneath said wall; and wall moving means comprising screws, each having one end attached to said wall and the opposite end attached to said stationary section, said wall moving means being situated at various floor levels in said building. 90

10. A device for moving a wall relative to a stationary section of a building embodying: movable wall supporting means; and means attached to said stationary section for moving said wall toward or away from said stationary section. 100

11. A device for moving a movable building unit relative to a stationary building unit embodying; supporting means for said movable unit; and means cooperatively interposed between said movable unit and said stationary unit for moving said movable unit toward or away from said stationary unit. 110

In testimony whereof, I have hereunto set my hand at Los Angeles, California, this 1st day of February, 1929. 115

GEORGE R. KRESS.
